UNITED STATES PATENT OFFICE

151,196

DESIGN FOR A SWING END FRAME

William I. Smith, Perrysburg, Ohio, assignor to
The Hettrick Manufacturing Company, Toledo,
Ohio, a corporation of Ohio

Application August 14, 1946, Serial No. 132,521

Term of patent 14 years

(Cl. D15—11)

To all whom it may concern:

Be it known that I, William I. Smith, a citizen of the United States and a resident of Perrysburg, Wood County, Ohio, have invented a new, original, and ornamental Design for a Swing End Frame, of which the following is a specification, reference being had to the accompanying drawing, forming a part thereof.

In the drawing:

Figure 1 is an inside perspective view of the swing end frame, showing my new design; and

Figure 2 is an outside perspective view of the swing end frame.

I claim:

The ornamental design for a swing end frame, as shown.

WILLIAM I. SMITH.
